FASTENING-INSERTING MACHINE

Elmer R. Pope, Hamilton, Mass., assignor to
 United Shoe Machinery Corporation, Paterson,
 N. J., a corporation of New Jersey

Application March 4, 1932, Serial No. 596,775

59 Claims. (Cl. 1—32)

My invention relates to machines for inserting fastenings in such work as shoes. It is particularly designed for the attachment of heels by nails driven from within the shoes.

5 An object of my invention is to improve generally the operation of such a machine and to render it readily adaptable for the insertion of nails or other fastenings in accordance with a wide range of designs, providing for the automatic supply of nails to the nailing mechanism, whatever the design for which the latter may be arranged, facilitating the vertical adjustment of the nail-drivers while maintaining a predetermined angular relation about their axes, and furnishing 10 means whereby the heels are firmly held in place during the driving of the nails.

In the attainment of this object I combine, as one feature of my invention, with a support, as a jack or nailing die of a heel-attaching machine 20 or a loader for such die, members, which may assume the form of nail-tubes, mounted to move upon the support, together with means arranged to position simultaneously a plurality of the members in accordance with a portion of a fastening-inserting design, and means operable independently of the first-mentioned means and arranged to position simultaneously a plurality of members different from those first acted upon in accordance with another portion of said fastening-inserting design. By thus organizing the fastening-receiving instrumentalities, the flexibility of the system is greatly increased, enabling the operator to set the members in certain formal 30 designs or to modify these, when, for example, the style of the heels as well as the size of the shoes change. By this means all the fastenings may be located most advantageously, thus obtaining in the heeling of shoes a secure attachment and a tight rand-crease. Further, by providing means 40 for compelling the plural positioning means to act together, the ratio of movement between one group and the other, when once established, may be maintained. In this way the operator having determined the best relation for a style of heel, 45 this may be continued for different shoe-sizes with manipulation of but a single positioning means. As applied to both the nail-tubes of the jack and of the loader of a heel-attaching machine, I have herein shown a guide member for 50 the tubes and a plurality of actuating members co-operating with the guide member and respectively movable in contact with different tubes. Preferably, the guiding and actuating effects are both furnished by slots in the members, the 55 actuating slots intersecting different groups of

guide-slots. When desired, locking means may compel the actuating members to move together. Regardless of whether or not the fastening-receiving members or nail-tubes are adjustable in groups, it is believed that the present invention presents patentable novelty in a loader which is movable from a nail-receiving position, which may be beneath the foot-plate of a nail-distributor, to a nail-delivering position over a nailing die or jack having movable members provided with nail-receiving passages and variable to correspond to different designs, the receiving members of the loader being adjustable to correspond to said receiving means of the die or jack. The loader is best movable under the power of the machine. As herein disclosed, the members consist of tubes pivoted at their upper extremities and having a member contacting with them below the pivots to vary the location of their lower ends. Thus the tubes are adapted to receive nails 20 from fixed delivery-passages at a distributor foot-plate and yet be brought into registration with variable receiving-passages in a nailing die.

In the inside nailing of heels, the shoes should be centralized transversely of the supporting jack 25 to symmetrically locate the points of insertion of the nails, and it is desirable to support the insoles at the sides of the heel-seat to prevent them from curling. As another feature of the invention, I thus position and support the work by the provision of a set of top-plates which may be separably mounted upon a jack-body, each plate of the set having transverse dimensions different from the associated plates and being provided with nail-receiving openings which, for the entire set, are 30 located in the same relation to one another in each plate. With an arrangement of adjustable nail-tubes such as has already been outlined, the nail-receiving passages in the plates are in the form of slots in which the tubes are movable.

The nail-drivers of machines for the inside attachment of heels are commonly inclined downwardly and inwardly at their upper nail-engaging extremities to produce a toeing-in of the nails when inserted in the work. This allows the 45 points at which the nails are driven to be kept well out toward the crease, without causing them to emerge through the peripheries of the heels. It is also desirable to locate each driver-end in a definite relation to the work-supporting surface, to sink the nail-heads in the insoles to the desired depth, and this positioning should be quite accurate to give the desired results. To accomplish this, as a further feature of this invention, I 50 associate with a driver and the carrier or plunger 55

in which it is mounted, means arranged to move said driver longitudinally of its axis, and a member contacting with the driver to retain it against rotation during such movement. By such an organization the inclined driver-end is kept always in the same angular relation circumferentially of the driver axis and the direction in which the nails are driven is kept constant, whatever the longitudinal adjustment may be. With a plurality of drivers, a member individual to each preferably provides for their longitudinal adjustment, while a member common to the plural drivers retains them against rotation during the longitudinal movement. The first of these members may be furnished by a nut threaded upon each driver and the second by a plate with a slot for each driver, there being a block movable in and retained against angular displacement in each of the slots, each block and driver having a co-operating slot and projection. By the use of a screw as positioning means for a non-rotatable driver, a very close setting may be obtained.

Still another feature of this invention may be found in means for applying pressure to a heel to hold it in place upon the heel-seat of a shoe during nailing. My improved heel-pressure comprises a head movable toward and from a shoe-support or jack, together with a plurality of heel-contact members mounted upon a carrier, an actuator arranged to move one of the contact members upon the carrier, both the carrier and actuator being movable on the head, and means forming a part of the head and arranged to move the carrier and actuator, preferably in opposite directions. As herein disclosed, one of the two contact members upon the carrier is pivoted for engagement by the actuating member. One of the contact members may be caused by the carrier to move directly into engagement with the heel to be attached, as against the tread-surface, and the pivoted member to be swung under the influence of the actuating member downwardly and inwardly against the back of the heel, effectively retaining said heel against being forced rearwardly from the heel-seat. The carrier and actuator appear herein as slides movable upon a pressure-head, the carrier-slide bearing both the tread-contact member and the pivoted rear contact member. The actuating slide engages the latter contact member to move it upon the carrier-slide, preferably through an interposed member, as a screw variable in position and thus altering the relative movement of the two members. To prevent a reverse movement of one of the contact members upon the carrier-slide when under pressure, as that at the rear of the heel, I may furnish means for locking such member through one of the slides, preferably the actuating slide, together with actuating means for releasing the lock. For the lock I preferably employ a detent mechanism connecting the chosen slide to the pressure-head. The releasing means is shown as a lever fulcrumed upon the head and engaged by a contact member upon the machine frame. Novel features embodied in way of illustration in this locking and releasing mechanism are covered generically in Letters Patent of the United States No. 1,895,896, dated January 31, 1933.

70 In the accompanying drawings,

Fig. 1 shows in broken perspective a portion of a heel-attaching machine embodying one form of my invention;

Fig. 2 is a broken perspective view of the upper 75 portion of the jack and its top-plate;

Fig. 3, a broken top plan view of the adjusting mechanism for the jack-tubes;

Fig. 4, a broken perspective view of such a mechanism for the loader-tubes;

Fig. 5, a vertical transverse section through the 5 jack, the loader and distributor-foot-plate, with the heel-pressure-head in elevation;

Fig. 6 shows separated from one another, the 10 elements for adjusting the drivers longitudinally; and

Fig. 7 is a side elevation of the upper portion of 15 the machine, particularly illustrating the pressure-abutment and its actuating mechanism.

The general heeling machine structure which I have illustrated is similar to that of Letters Patent of the United States No. 1,545,575, Stan-dish, July 14, 1925, there being a jack or work-support 10 rising from a frame 11 and having re-ciprocating within it under the power of the machine, a driver-plunger or carrier 12. Upon the 20 top of this plunger is a plate 13 from which rises vertical nail-drivers 14. There is also a pres-ure-head 16 movable by the machine to clamp a heel to be attached upon the heel seat of a jacked shoe. I prefer to arrange the machine 25 for power-loading, such an organization as that disclosed in Letters Patent No. 1,785,928, Benja-min, December 23, 1930 being suitable. Of this there appears a foot-plate 18 to the nail-receiving passages of which lead tubes 20 from a nail-distributor (not illustrated). An automatically actuated shutter 22 supports the nails at the foot-plate until they are ready to be delivered to a 30 loader-block 24 movable by a slide 26 from a re-ceiving position beneath the foot-plate to a de-livering-position over the jack. During this 35 transfer by the loader-block the nails are held ready for delivery upon an automatically con-trolled shutter 28.

Across the jack, just above the upper end of 40 the plunger 12, extends a plate 30 carrying ver-tical nail-and driver-receiving tubes. These tubes are shown as four in number. Of these there is a pair 32, 32 corresponding to the breast-nails and a succeeding intermediate pair 34, 34. 45 There is also an opening 36 to receive the rear driver. The tubes 32 and 34 are flanged at their lower extremities to be guided respectively in slots 38, 38 and 40, 40 in the plate 30, these slots having upper walls overhanging the flanges and retaining 50 the tubes against upward displacement. The direction of extension and length of the slots is such that the tubes may be moved to position them for the insertion of nails in accordance with every design which it is desired to employ. Mov-able in the same horizontal plane upon the top 55 of the plate 30 are two actuating members in the form of cam-slides 42 and 44, the first provided with a pair of slots intersecting vertical planes through the plate-slots 38, and the second simi-larly related to the plate-slots 40 (Fig. 3). Each 60 slide contains a horizontal threaded opening, that of the breast-tube-slide receiving an externally threaded sleeve 46 mounted to turn upon the front of the plate 30, while the intermediate-tube slide has threaded into it a spindle 48 rotatable within the sleeve. Both the sleeve and spindle are held against longitudinal movement. Formed up-on the outer end of the sleeve is a head or finger-piece 50, and just outside this is a head 52 fast upon the spindle. Each head is shown as bearing a scale, the graduations of which may indicate 65 positions for the respective pairs of tubes in differ-ent nailing designs. The graduations may be re- 70 75

ferred to index-points 54 formed upon brackets or upon the jack. The sleeve and spindle may be rotated independently to position each pair of tubes separately, or they may be compelled to rotate 5 together to simultaneously adjust both pairs by a coupling or locking pin 56 threaded through the head 52 so its inner point may enter or be removed from a registering opening in the head 52. By the separate rotation of the sleeve and spindle 10 the slides 42 and 44 may be moved from front to rear of the plate 30, their slots are thus differently located longitudinally of the guide-slots 38 and 40. This cams the tubes 32 and 34 along said slots to different positions, the movement of the 15 tubes of each pair being in opposite directions transversely of the jack. It will be seen that this adjustment of driver-tubes in independent groups permits the operator to not only change the nail-ing design as the shoe and its heel vary in size, 20 but also to meet the requirements of heels of different contours by adjusting the pairs of breast-nail-tubes and intermediate tubes independently of each other, and thereby bring all in the desired close relation to the crease. Furthermore, the 25 best relation having been established, the two adjusting devices may be coupled by the pin 56 to move together, and the chosen ratio maintained for different heel-sizes.

In addition to their passage through the slots 30 38 and 40 of the plate 30, the tubes 32 and 34 receive the guidance of a top-plate 60 of the jack, in which plate are pairs of slots 62 and 64 lying respectively in the same vertical planes as the plate-slots 38 and 40 (Fig. 2). Through this plate 35 60 the upper extremities of the tubes just emerge to allow the insole of a jacked shoe to bear upon them. An opening 66 in the top-plate receives the rear driver, which is shown as non-adjustable laterally. Together the plate 60 and the tubes 40 may be viewed as the equivalent of a nailing die. It is desirable to hold the jacked shoe against lateral movement, so nailing may be centralized, and also to support the edges of the insole at the 45 heel-seat against being bent down during the heeling operation. To accomplish this, I preferably provide a set of top-plates which, while they may be of the same length from front to rear of the jack, have different transverse dimensions. They may be held in place, to be readily 50 interchangeable, by an engaging projection and slot 68 at the rear and a projection and opening 70 at the front, a spring-actuated pin 72 cooperating with the projection to separably lock the top upon the jack. In Fig. 2 the smallest size of 55 top-plate appears, and in Fig. 1 a larger size.

One of the drivers 14, that at the rear, is fixed 60 against lateral movement in the plate 13, while the companion drivers are movable in slots 80 in the plate. To give the desired inward inclination to the nails, as appears at N in Fig. 7, the ends of the drivers which engage the nail-heads are inclined downwardly and inwardly toward the vertical axis of the jack. The extent 65 to which the driver-ends emerge from the top of the jack is best variable, so the heads of the attaching nails may be sunk below the surface of the insole. To maintain the inclined end-surfaces in correct relation to the periphery of the jack and to the work, the drivers should be kept 70 from turning about their longitudinal axes while the vertical adjustment is being made, and this retaining means should not interfere with the attainment of a relatively fine adjustment. I accomplish this result in the following manner: 75

The plate 13 has fast upon and spaced from it

an upper section 82 provided with slots 84 registering with the slots 80 in the main portion of the plate. The foot of each laterally adjustable driver enters an opening in a guide-block 86 movable in one of the slots 80. Each driver is slotted longitudinally as is indicated at 88 (Fig. 6) and entering this slot is a projection 90 lying in an opening in a retaining-block 92 which surrounds the driver, such block being movable in one of the slots 84. By this means each pair of 10 members 86 and 92 and the associated driver is guided for lateral adjustment, and at the same time the driver is held by the projection 90 against rotation within the slot of the retaining section 82. To produce the longitudinal adjustment of the driver, it is threaded at 94, and upon this thread a nut 96 is arranged to turn between the plate 13 and its section 82. Above the section 82 a nut 98 is threaded on the rod. By turning the nut 96 the rod may be adjusted longitudinally 20 to any extent desired without rotation and may be locked in the position thus attained by the nut 98. The relation of the projection 90 to the slots 80, 84 and corresponding guide-slots in the jack is such as to hold the driver with its inclined nail-engaging end always in the chosen angular position about the axis of the driver. 25

The loader-block 24 is arranged to receive nails from the distributor-foot-plate 18 through a group of unvarying passages and to deliver them 30 to the jack-tubes in whatever positions these may have been adjusted. The block has an upper section 100 (Fig. 5) between which and the main portion 24 of the block the shutter 28 is movable. The block-section 100 is shown as having 35 vertical passages 102 so positioned as to register with the foot-plate-openings of the distributor tubes 20, when the loader is in its rearward nail-receiving relation. In the body of the loader are recesses 104 vertically aligned with the passages 40 102 and which contain the heads 106 of nail-tubes 108. These heads are curved upon their upper and under sides and so engage the opposed walls that the tubes are mounted for universal oscillation. They are guided to swing in inclined slots 45 110 in pairs corresponding to the top-plate-slots 62 and 64 and are movable in said slots by cam-plates 112 and 114 (Fig. 4), respectively controlled through heads or finger-pieces 116 and 118 and threaded actuating members, precisely as 50 in the adjustment of the jack-tubes. The graduations on the tube-setting heads of the loader mechanism may be the same as upon those of the jack, so the operator, upon setting the jack-tubes for a particular nailing, can, with little effort, 55 correspondingly position the loader-tubes. To the latter the distributor supplies its nails, without change, to the upper pivoted ends through the passages 102 and these loader-tubes, by their gradual inclination between their upper and lower extremities, transfer their nails from one fixed arrangement of tubes to variable designs 60 without danger of causing clogging.

In the attachment of heels by inside nailing there is, on account of the inclination of the tread-surface of heels with respect to the heel-seat, this being as illustrated by the heel H and shoe S in Fig. 7, a constant force tending to displace the heels rearwardly. My improved pressure abutment is especially designed to resist this tendency. 65 Mounted to move vertically in the head 16 is a carrier-slide 120 which has adjustable at its lower extremity, as to its angle from front to rear of the machine, a carrier-block 122. Movable in ways extending transversely of the under side of 70 the block, so vertical alinement with the jack may 75

be attained, is a member 124 furnishing one section of a universal joint, a second joint-section 126 being movable therein. A contact-plate 128 is drawn against the under side of the member 126 by a tension-spring 130 joining the plate and block through openings in the joint-sections. The plate 128 furnishes a member for contact with the tread-surface of the heel. Pivoted at 132 upon the carrier-slide above the block 122 is an arm 134, and secured upon this arm is a holder 136 for a rear heel-contact member 138, which preferably consists of a padded fork shown as adjustable angularly about a pivot-pin 140. Movable in the head 16 in a direction parallel to the carrier-slide 142 is an actuating slide 142, joined to move simultaneously with the carrier-slide but oppositely thereto by gearing 144. The lower extremity of the slide 142 has a contact member 146, which may be furnished by a screw and is therefore adjustable. The head upon this screw bears against a substantially horizontal surface 148 upon the holder 136 of the rear heel-contact member. This engagement is yieldably maintained by a tension-spring 150 joining the holder to the head 16. The spring elevates the slide 142 until its movement is stopped by a screw 149 threaded through the top the head. This, through the gearing 144, correspondingly depresses the carrier-slide. When, in the operation of the machine, the head is lowered to apply pressure to the heel H situated upon the heel-seat of the jacked shoe S, the tread-plate 128 first contacts with the heel and the slide 142 yields, the gearing 144 forcing the slide 142 down. The spring 150 is at this time holding the rear contact member 138 away from the heel, the normal position being determined by the adjustment of the screw 146. As the actuating slide descends, the pressure of the screw against the surface 148 turns the arm 134 about its pivot, swinging the member 138 downwardly and inwardly against the back of the heel, this continuing until the forces applied to the heel by the two slides through their contact members are equalized. Of these forces there will always be a substantial component produced by the forward-movement of the member 138 about its pivot, which will directly oppose rearward displacement of the heel. Means is included in the abutment for positively locking the rear contact member 50 against yielding upon its pivot during the application of pressure. For this purpose the actuating slide 142 has associated with it detent mechanism, comprising a rack 152 mounted upon the head 16 and having engaging its downwardly inclined teeth two detents with their ends staggered vertically to give their retaining effect in shorter steps. The slide 142 is thereby held against upward travel, maintaining the screw 146 as a fixed abutment which locks the holder 136 and the rear contact member so it cannot swing outwardly. Rearward displacement of the heel upon the heel-seat is thus positively prevented. One of the detents numbered 154 is secured to a shaft 156 rotatable in the slide 142, 60 while the companion detent 158 is free to turn about the shaft. This detent 158 is urged against the rack by a spring 160, and has a projection 162 which extends outside the detent 154 to receive its contact when the latter is separated from the rack. Secured to one extremity of the shaft 156 is an arm 164 (Fig. 1) having a lateral projection 166 entering an opening in a block 167 guided in a slot in a normally substantially vertical arm 168 of a lever 170 fulcrumed upon the head. During the movement of the slide 142 the projection 166 may travel freely along the slot. A spring 172 exerts its force to hold the lever raised and by pressing the forward wall of the slot against the block 167 forces the detent 154 into engagement with the rack 152. When, after a heel operation, the head 16 rises to remove the pressure from the work, a projection 174 from the lever 170 strikes a horizontally extending contact member 176 which may be adjustably secured to the frame 11 by slot-and-screw connections 178. This engagement urges the rear wall of the slot in the lever arm 168 against the block 167, rotating the shaft 156 anti-clockwise (Fig. 7) and withdrawing the detent 154 from the rack. The detent 154, by engagement with the projection 162, releases the associated detent 158, leaving the slide 142 free to assume its normal position.

Except for the novel features with their various adjustments which have already been discussed, the operating procedure in connection with the machine of this invention may be similar to those of the Standish and Benjamin patents previously mentioned and requires no description.

Having described by invention, what I claim as new and desire to secure by Letters Patent of the United States is:

1. In a fastening-inserting machine, a support, members mounted to move upon the support and having fastening-receiving passages, means arranged to position simultaneously a plurality of the members in accordance with a portion of a fastening-inserting design, and means operable independently of the first-mentioned means and arranged to position simultaneously a plurality of members different from those first acted upon in accordance with another portion of such fastening-inserting design. 30
2. In a fastening-inserting machine, a support, members mounted to move upon the support and having fastening-receiving passages, means arranged to position certain of the members in accordance with a portion of a fastening-inserting design, means operable independently of the first-mentioned means and arranged to position certain other of the members in accordance with a different portion of such fastening-inserting design, and means for compelling the positioning means to act together. 40
3. In a heel-attaching machine, a nailing die, nail-tubes mounted to move in the die, a member movable in engagement with a group of tubes to position said tubes in accordance with a portion of a nailing design, and a member movable in engagement with a different group of tubes to position such group of the tubes in accordance with another portion of the nailing design. 50
4. In a heel-attaching machine, a traveling nail-loader, nail-tubes mounted to move upon the loader, means arranged to position a group of the tubes in accordance with a portion of a nailing design, and means operable independently of the first-mentioned means and arranged to position another group of tubes in accordance with a different portion of such nailing design. 60
5. In a fastening-inserting machine, co-operating supports, members mounted to move on each support and having fastening-receiving passages, the passages of the members on one support delivering fastenings to the passages of the members on the other support, means arranged to position certain of the members upon each support in accordance with a portion of a fastening-inserting design, and means operable independently of the first-mentioned means and arranged to position 70

certain other of the members upon each support in accordance with a different portion of such fastening-inserting design.

6. In a fastening-inserting machine, co-operating supports, members mounted to move on each support and having fastening-receiving passages, means arranged to position certain of the members upon each support in accordance with a portion of a fastening-inserting design, means operable independently of the first-mentioned means and arranged to position certain other of the members upon each support in accordance with a different portion of such fastening-inserting design, and means for causing the positioning means of both supports to act simultaneously.

7. In a heel-attaching machine, a nailing die, nail-tubes mounted to move in the die, means arranged to position a group of the tubes in accordance with a portion of a nailing design, means operable independently of the first-mentioned means and arranged to position another group of the tubes in accordance with a different portion of such a nailing design, a traveling nail-loader delivering to the die, nail-tubes mounted to move upon the loader, means arranged to position a group of the loader-tubes to correspond to a group of the die-tubes, and means operable independently of the first-mentioned loader-tube-positioning means and arranged to position another group of the loader-tubes to correspond to the second group of die-tubes.

8. In a fastening-inserting machine, a support, a guide member carried by the support, fastening-receiving tubes movable upon the guide member, and a plurality of actuating members co-operating with the guide member and being respectively movable in contact with different tubes.

9. In a fastening-inserting machine, a support, a guide member carried by the support, fastening-receiving tubes movable upon the guide member, a plurality of actuating members co-operating with the guide member and being respectively movable in contact with different tubes, and latching means for causing the actuating members to move together.

10. In a fastening-inserting machine, a support, a guide member carried by the support and provided with slots, fastening-receiving tubes movable in said slots, a plurality of actuating members each having tube-receiving slots intersecting the planes of different groups of guide-slots, and means arranged to move the actuating members independently of each other.

11. In a heel-attaching machine, a jack, nail-tubes mounted therein, a guide-plate fixed in the jack and having slots through which the nail-tubes pass, and two cam-plates slideable upon the jack and each having slots receiving groups of tubes different from the associated cam-plate.

12. In a heel-attaching machine, a loader-block, nail-tubes movable therein, a guide-plate fixed in the loader-block and having slots through which the nail-tubes pass, and two cam-plates slideable upon the block and each having slots receiving groups of tubes different from the associated cam-plate.

13. In a heel-attaching machine, a jack, nail-tubes mounted therein, a guide-plate fixed in the jack and having slots through which the nail-tubes pass, two cam-plates slideable upon the jack and each having slots receiving groups of tubes different from the associated cam-plate, and loading mechanism including a loader-block traveling from a nail-receiving position to a nail-delivering position over the jack, nail-tubes mov-

able upon the loader-block, a guide-plate fixed upon the loader-block and having slots which register with the guide-plate-slots of the jack in the delivering position of the loader-block and two-cam-plates slideable upon the block and each having tube-receiving slots corresponding respectively to those of the cam-plates of the jack.

14. In a nailing machine, a support, nail-tubes movable thereon, a guide member fixed upon the support and having slots through which the nail-tubes pass, a threaded sleeve rotatable upon the support, a threaded spindle rotatable in the sleeve, a cam member having threaded engagement with the sleeve and provided with slots co-operating with certain of the guide member slots, and a cam member having threaded engagement with the spindle and provided with slots co-operating with other of the guide member slots.

15. In a nailing machine, a support, nail-tubes movable thereon, a guide member fixed upon the support and having slots through which the nail-tubes pass, a threaded sleeve rotatable upon the support, a threaded spindle rotatable in the sleeve, locking means for separably connecting the spindle and sleeve, a cam member having threaded engagement with the sleeve and provided with slots co-operating with certain of the guide member slots, and a cam member having threaded engagement with the spindle and provided with slots co-operating with other of the guide member slots.

16. In a heel-attaching machine, a jack having nail-receiving means movable thereon, a loader movable from a nail-receiving position to a nail-delivering position, said loader being provided with movable members in which are nail-receiving passages, and means arranged to adjust the members to different positions upon the loader to correspond to the nail-receiving means of the jack.

17. In a heel-attaching machine, a loader movable from a nail-receiving position to a nail-delivering position, said loader being provided with movable tubes in which are nail-receiving passages, and a member contacting with a plurality of the tubes and movable to change their positions on the loader simultaneously.

18. In a heel-attaching machine, a loader movable from a nail-receiving position to a nail-delivering position, said loader being provided with tubes pivoted at their upper extremities and each having a nail-receiving passage, and a member contacting with the tubes below their pivots and being movable to vary the location of their lower ends.

19. In a heel-attaching machine, a die provided with nail-passages, a loader movable from a nail-receiving position to a nail-delivering position over the die, said loader being provided with movable members in which are nail-receiving passages, and means arranged to adjust the loader members to correspond to the passages in the die.

20. In a heel-attaching machine, a die provided with nail-passages variable in position, a loader movable from a nail-receiving position to a nail-delivering position over the die, said loader having movable nail-tubes, and means arranged to vary the position of the loader-tubes to correspond to the die-passages.

21. In a heel-attaching machine, a jack provided with nail-receiving tubes, means arranged to move the tubes to position the nails in accordance with different designs, and a movable loader provided with nail-holding elements variable in

position upon said loader to supply nails to the jack for all the designs to be nailed.

22. In a heel-attaching machine, a jack provided with nail-receiving tubes, means arranged to move the tubes to position the nails in accordance with different designs, a movable loader provided with nail-holding elements variable in position upon said loader to supply nails to the jack for all the designs to be nailed, and means for moving the loader and its variable elements under the power of the machine to cause nail-delivery to the jack.

23. In a heel-attaching machine, a foot-plate in which are nail-delivering passages maintained in a constant relation, a jack provided with nail-tubes variable in position, a loader-block movable from a nail-receiving position beneath the foot-plate to a nail-delivering position over the jack, said loader-block having nail-tubes pivoted at their upper extremities for registration with the foot-plate-passages, and means for moving the lower ends of the loader-block-tubes to register with the jack-tubes in different locations.

24. In a heel-attaching machine, a jack having a body-portion, a top-plate belonging to a set of interchangeable top-plates arranged to be individually applied to the jack-body, each of said plates having transverse dimensions different from the associated plates and being provided with a group of nail-receiving openings, the openings of all plates being located in the same relation to one another, and means for separably connecting any one of the top-plates to the jack-body.

25. In a heel-attaching machine, a jack having a body-portion, a top-plate belonging to a set of interchangeable top-plates arranged to be individually applied to the jack-body, each of said plates having the same dimensions from front to rear of the jack and different dimensions laterally thereof and being provided with nail-receiving openings, the openings of all the plates of the set being located in the same relation to one another, and means for separably connecting any one of the top-plates to the jack-body.

26. In a heel-attaching machine, a jack having a body-portion, a top-plate belonging to a set of interchangeable top-plates arranged to be individually applied to the jack-body, each of said plates having transverse dimensions different from the associated plates and being provided with slots, the slots of all the plates being located in the same relation to one another, nail-tubes supported upon the jack-body and being movable along the slots, and means for separably connecting any one of the top-plates to the jack-body.

27. In a heel-attaching machine, a jack having a body-portion, a top-plate belonging to a set of interchangeable top-plates arranged to be individually applied to the jack-body, each plate of the set having transverse dimensions different from the associated plates and being provided with slots, means for separably connecting any one of the top-plates to the jack-body, a plunger reciprocating in the jack-body, tubes movable in the jack-body and extending into the top-plate-slots, drivers operating in the tubes and being movable upon the plunger, and means mounted upon the jack-body for moving the tubes and drivers along the top-plate-slots to correspond to different nailing designs.

28. In a heel-attaching machine, a carrier, a nail-driver movable upon the carrier and having

an inclined end for contact with the nails to be driven, and means arranged to move the driver upon the carrier longitudinally of its axis while maintaining the inclined end in the same angular relation circumferentially of the axis.

29. In a heel-attaching machine, a carrier, a nail-driver movable upon the carrier, means arranged to move the driver upon the carrier longitudinally of its axis, and a member contacting with the driver to retain it against rotation during such movement.

30. In a heel-attaching machine, a carrier, a plurality of nail-drivers movable upon the carrier, a member individual to each driver and arranged to move it upon the carrier longitudinally of its axis, and a member common to plural drivers and co-operating with them to retain them against rotation during the longitudinal movement.

31. In a heel-attaching machine, a jack, a nail-tube movable transversely thereof, a plunger movable longitudinally of the jack, a driver carried by the plunger, said driver operating in the tube and being movable therewith, means rotatable upon the driver for moving it longitudinally upon the plunger, and means engaging the driver during its transverse movement for preventing its rotation.

32. In a heel-attaching machine, a jack, a nail-tube movable transversely thereof, a plunger movable longitudinally of the jack, a driver carried by the plunger, said driver operating in the tube and being movable therewith, means arranged to move the driver upon the plunger longitudinally of its axis, and means engaging the driver during its transverse and longitudinal movement for preventing its rotation.

33. In a heel-attaching machine, a jack, a plunger movable longitudinally of the jack, a driver carried by the plunger, means for moving the driver longitudinally upon the plunger, and means for retaining the driver against rotation during such movement, said retaining means and driver being provided with a co-operating slot and projection.

34. In a heel-attaching machine, a jack, a plunger movable longitudinally of the jack, a threaded driver carried by the plunger, a retaining member for the driver, said retaining member and driver being provided with a cooperating slot and projection, and a nut engaging the driver-thread and contacting with the retaining member.

35. In a heel-attaching machine, a jack, a plunger movable longitudinally of the jack, a threaded driver carried by the plunger, a retaining member for the driver, said retaining member and driver being provided with a co-operating slot and projection, and nuts engaging the driver-thread and contacting with opposite sides of the retaining member.

36. In a heel-attaching machine, a jack, nail-tubes movable transversely thereof, a plunger movable longitudinally of the jack, a driver carried by the plunger and operating in each nail-tube, each driver being movable with its tube, a retaining block for each driver, said block and driver being provided with a co-operating slot and projection, and a retaining plate having slots in which all the blocks are movable.

37. In a heel-attaching machine, a jack, a plurality of nail-tubes movable transversely thereof, a plunger movable longitudinally of the jack and carrying a slotted driver-plate, drivers operating in the tubes and movable longitudinally of the

slots, and a retaining member engaging each driver and movable in its plunger-slot, such retaining member while in the slot positively locking the corresponding driver against rotation.

5 38. In a heel-attaching machine, a jack, a plurality of nail-tubes movable transversely thereof, a plunger movable longitudinally of the jack, said plunger carrying a slotted driver-plate and being formed in spaced sections provided with pairs of 10 registering slots, a driver operating in each tube and lying in a pair of slots, a guide-block for each driver movable in a slot in one plate-section, and a retaining block for each driver movable in a slot in the other plate-section.

15 39. In a heel-attaching machine, a jack, a plurality of nail-tubes movable transversely thereof, a plunger movable longitudinally of the jack, said plunger carrying a slotted driver-plate and being formed in spaced sections provided with pairs of 20 registering slots, a threaded driver operating in each tube and lying in a pair of slots, a guide-block for each driver movable in a slot in one plate-section, a retaining block for each driver movable in a slot in the other plate-section, and a pair of nuts threaded upon each driver at opposite sides of the retaining block.

25 40. In a heel-attaching machine, a shoe-support, and a heel-pressure head movable toward and from the support and having heel-contact members, a carrier for plural contact members movable on the head, an actuator movable on the head and arranged to move one of the contact members upon the carrier and means forming a part of the head and arranged to move the carrier and actuator.

35 41. In a heel-attaching machine, a shoe-support, and a heel-pressure device co-operating with the support and having a carrier and an actuator movable upon it, a heel-contact member mounted upon the carrier, a second heel-contact member pivoted upon the carrier and engaged by the actuator and means arranged to move the carrier and actuator in opposite directions.

40 42. In a heel-attaching machine, a shoe-support, and a heel-pressure device co-operating with the support and having heel-contact members, a movable carrier for plural contact members, a movable actuator arranged to move one of the contact members upon the carrier and in one direction only, a yieldable member connecting such contact member and another portion of the pressure device and means arranged to move the carrier and actuator.

45 43. In a heel-attaching machine, a shoe-support, and a heel-pressure device co-operating with the support and having a carrier and an actuator movable upon it, a heel-contact member mounted upon the carrier, a second heel-contact member pivoted upon the carrier, means for forcing the second heel-contact member and actuator into yieldable engagement and means arranged to move the carrier and actuator in opposite directions.

50 44. In a heel-attaching machine, a shoe-support, and a heel-pressure device co-operating with the support and having a carrier and an actuator movable upon it, a heel-contact member mounted upon the carrier, a second heel-contact member pivoted upon the carrier and engaged by the actuator, an interposed member variable in position to receive such engagement and means arranged to move the carrier and actuator in opposite directions.

55 45. In a heel-attaching machine, a heel-pressure-head, a slide movable upon the head, a

tread-contact member mounted upon the slide, a rear contact member pivoted upon the slide, and a second slide movable upon the head and engaging the rear contact member.

46. In a heel-attaching machine, a heel-pressure-head, a slide movable upon the head, a tread-contact member mounted upon the slide, a rear contact member pivoted upon the slide, a second slide movable upon the head and engaging the rear contact member, and a spring joining the rear contact member to the head. 5

47. In a heel-attaching machine, a heel-pressure-head, a slide movable upon the head, a tread-contact member mounted upon the slide, a rear contact member pivoted upon the slide, a second slide movable upon the head and engaging the rear contact member, a screw threaded into the second slide and being engaged by the rear member, and means for yieldably forcing the screw and the rear contact member together. 10 15

48. In a heel-attaching machine, a heel-pressure-head, a slide movable upon the head, a tread-contact member mounted upon the slide, universal connections between the tread-contact member and the slide, a rear contact member pivoted upon the slide, and a second slide movable upon the head and engaging the rear contact member. 20 25

49. In a heel-attaching machine, a heel-abutment having co-operating members furnishing a universal joint, means for securing one of the joint-sections in place upon the abutment, a heel-contact plate engaging the other joint-section, and yieldable means for connecting the plate and abutment to hold the plate and joint assembled. 30 35

50. In a heel-attaching machine, a heel-abutment having co-operating members furnishing a universal joint, means for securing one of the joint-sections in place upon the abutment, a heel-contact plate engaging the other joint-section, 40 and a spring passing through the joint-sections and connected to the plate and abutment.

51. In a heel-attaching machine, a heel-pressure-head, two slides movable upon the head, two heel-contact members mounted upon one of the slides for respective engagement with the tread-surface and rear of a heel, connecting means for the slides, and means for locking one of the slides against movement in one direction. 45

52. In a heel-attaching machine, a heel-pressure-head, two slides movable upon the head, two heel-contact members mounted upon one of the slides for respective engagement with the tread-surface and rear of a heel, connecting means for the slides, means for locking the second slide against movement in one direction, 50 and means operable upon movement of the head for releasing the lock.

53. In a heel-attaching machine, a heel-pressure-head, a slide movable upon the head, two heel-contact members mounted upon said slide, a second slide movable upon the head in engagement with one of the contact members, and a second slide. 55 60

54. In a heel-attaching machine, a heel-pressure-head, two slides movable upon the head, two heel-contact members movable by the slides, a member mounted upon such slide and acting upon the detent mechanism to release the slide upon movement of the head. 70

55. In a heel-attaching machine, a heel-pressure-head, a slide movable upon the head, a tread-contact member mounted upon the slide, a

rear contact member pivoted upon the slide, a second slide movable upon the head and engaging the rear contact member, and a detent mechanism connecting the head and said second slide.

5 56. In a heel-attaching machine, a frame, a pressure-head movable thereon, a heel-contact member mounted upon the head, an actuating member for the contact member, a detent pivoted upon the actuating member, and a rack carried by the head and engaged by the detent.

10 57. In a heel-attaching machine, a frame, a pressure-head movable thereon, a heel-contact member mounted upon the head, an actuating member for the contact member, a detent pivoted upon the actuating member, a rack carried by the head and engaged by the detent, an arm fixed to the detent-pivot, and means contacting with the arm for separating the detent from the rack.

58. In a heel-attaching machine, a frame, a pressure-head movable thereon, a heel-contact member mounted upon the head, an actuating member for the contact member, a detent pivoted upon the actuating member, a rack carried by the head and engaged by the detent, an arm fixed to the detent-pivot, a lever fulcrumed upon the head and co-operating with the detent arm, and a contact member upon the frame engaged by the lever.

10 59. In a heel-attaching machine, a work-support, a pressure-head cooperating therewith, a member movable by the head into contact with the tread-surface of a heel to be attached, a member movable upon the head into contact with the rear surface of said heel, and a lock arranged to prevent reverse movement of the rear contact member.

ELMER R. POPE.
